UNITED STATES PATENT OFFICE.

PHILLIP A. SHAVER, OF PUENTE, CALIFORNIA.

MAIL CATCHING AND DELIVERING APPARATUS.

1,229,331.

Specification of Letters Patent. Patented June 12, 1917.

Application filed December 8, 1916. Serial No. 135,836.

To all whom it may concern:

Be it known that I, PHILLIP A. SHAVER, a subject of the King of Great Britain, residing at Puente, in the county of Los Angeles 5 and State of California, have invented certain new and useful Improvements in Mail Catching and Delivering Apparatus, of which the following is a specification.

This invention relates to mail catching 10 and delivering apparatus, and the primary object is to provide improved means for receiving mail from fast moving trains whereby the mail bags will be received by the receiving apparatus in suspended position so 15 that no injury will be done to the mail within the mail bag.

Another object of the invention is to provide a means for delivering a plurality of mail bags simultaneously with one operation 20 of the delivering and receiving apparatus, the receiving and delivering elements acting in coöperation with a carrier designed to carry a plurality of bags and adapted to be deposited with the bags at the receiving station.

A further object of the invention is the provision of a mail delivering apparatus carried within the mail car and mounted to permit the apparatus to be projected from 30 either side of the mail car whereby the mail may be delivered to receiving stations at either side of the railway.

With these objects in view, together with others which will appear as the description 35 proceeds, the invention resides in the novel formation, combination, and arrangement of parts, all as will be described more fully hereinafter, illustrated in the drawings, and particularly pointed out in the claims.

40 In the drawings:—

Figure 1 is a fragmentary vertical section through the mail car showing my invention applied;

Fig. 2 is a fragmentary plan view of the 45 delivering and receiving apparatus;

Fig. 3 is a detail fragmentary perspective view of one end of the delivering apparatus;

Fig. 4 is a fragmentary perspective view of the tower for the receiving station; and

50 Fig. 5 is a detail side elevation of one of the carriers.

Referring to the drawing, wherein is

illustrated the preferred form of my invention, the mail car A is provided at its top on the interior with a transverse supporting beam 1. Fastened to the beam 1 is a suspending track 2 which comprises a plate 3 having a channel 4 formed on its lower side, the channel being embraced by curved flanges 5 and 6. Slidably mounted for longitudinal movement in the trackway or channel 4 is a conveyer 7 having longitudinal tongues formed on each edge and disposed within the curved flanges 5 and 6.

A delivering apparatus is mounted on 65 each end of the conveyer 7 and, therefore, for the purposes of this description only one of the delivering apparatuses will be described. An angle iron 8 has one flange fastened to the end of the conveyer 7 and 70 the opposite flange depends vertically and is fastened to the flanges 9 of a pair of retaining plates 10 having their proximate faces in engagement. The two members 10 are disposed edgewise as clearly shown by 75 Fig. 3 of the drawings and supported by a supporting plate 11 disposed in a horizontal plane and adapted to assist the plates 10 in supporting the mail bag carriers. Right angular sleeves 12 are provided with ears 80 through which bolts or fastening rivets are projected for fastening the sleeves 12 to the plates 10 and 11. The sleeves 12 are arranged in pairs on each side of the plate 11. Spring clips 13 are provided for supporting 85 the mail bag carriers, and each clip comprises a heavy curved wire 14 having its intermediate portion coiled to provide the springs 15 while the ends of the wire are bent at right angles and embraced by one of 90 the angular sleeves 12. The outer terminal of each member 14 is curved outwardly to permit the mail bag carrier to pass between each pair of clip arms. Each mail bag carrier is constructed from a hollow tubular 95 member that is substantially ovoid in cross section. Two annular depressions or grooves 16 are formed in the tubular member, and by referring to Fig. 5 of the drawing, it will be observed that the wall at one side of the groove is disposed at a considerably 100 sharper angle than is the opposite side of the groove. The wall 17 of each groove rests upon the arms of the spring clips when

the carrier is delivered or received by the apparatus. It will be understood that these carriers are interchangeable, and therefore they may be used either for delivering mail 5 from the mail car or for receiving mail by the receiving apparatus at the side of the railway. Depending from the bottom of each carrier is a plurality of hangers 18 which are adapted to be connected to the 10 rings generally carried by the common type of mail bag so that a plurality of mail bags may be attached to each carrier.

Mounted at the side of the railway, and embedded in a suitable concrete foundation 15 19, is a tower 20. The top of the tower carries a rectangular plate 21 which has a right angularly extending flange 22 depending from one edge thereof, and which is identical in construction with the depending flange 20 of the angle iron 8. This flange carries a receiving and delivering structure that is identical in construction with the delivering structure previously described, this relative construction being clearly shown by Fig. 2 25 of the drawing. In this connection, it is pointed out that the only difference in the delivering and receiving apparatus lies in the plane in which they are disposed, since the delivering apparatus on the mail car is disposed in a higher plane than the receiving apparatus on the tower for permitting 30 the apparatuses to pass each other.

I claim:

1. A mail transferring device comprising, 35 a mail bag supporting device mounted within a mail car and adapted to project from either side thereof, a supporting plate carried by the end of the mail bag supporting device, right angular sleeves fastened to the 40 supporting plate, and spring clips having right angular end portions embraced by the said right angular sleeves.

2. A mail transferring device comprising, 45 a mail bag supporting device mounted within a mail car and adapted to project from either side thereof, a supporting plate carried by the end of the mail bag supporting device, a pair of retaining plates disposed edgewise on the supporting plate and having 50 their proximate faces in engagement, right angular sleeves mounted upon the supporting plate and the said retaining plates, and supporting elements engageable with the right angular sleeves and supported 55 thereby.

3. A mail transferring device comprising, 60 a mail bag supporting device mounted within a mail car, one end of the mail bag supporting device carrying a length of angle iron having one flange depending vertically 65 from the end of the mail bag supporting device, retaining plates comprising right angularly bent members each having one of their flanges fastened to the depending flange of the said angle iron, the proximate faces

of the other flanges being in engagement, spring clips, means for attaching the spring clips to the said retaining plates, the said means including fastening elements projected through the engaging portions of the retaining plates and connected to the said means. 70

4. A mail transferring device comprising, a mail bag supporting device, retaining plates carried by the mail bag supporting device, said plates having projecting flanges which latter have their proximate faces in engagement, right angular sleeves connected to the said retaining plates, and spring clips carried by the right angular sleeves. 75

5. A mail transferring device comprising, 80 a mail bag supporting device, retaining plates carried by the mail bag supporting device, said plates having projecting flanges which latter have their proximate faces in engagement, right angular sleeves connected 85 to the said retaining plates, the said sleeves being arranged in pairs on each side of said retaining plates, and a spring clip carried by each of said sleeves.

6. A mail transferring device comprising, 90 a mail bag supporting device, retaining plates carried by the mail bag supporting device, said plates having projecting flanges which latter have their proximate faces in engagement, right angular sleeves connected 95 to the said retaining plates, the said sleeves being arranged in pairs on each side of said retaining plates, a spring clip carried by each of said sleeves, each clip being constructed from a length of wire having one 100 end bent at right angles and embraced by one of the said sleeves.

7. A mail transferring device comprising, a mail bag supporting device, retaining plates carried by the mail bag supporting 105 device, said plates having projecting flanges which latter have their proximate faces in engagement, right angular sleeves connected to the said retaining plates, the said sleeves being arranged in pairs on each side of said 110 retaining plates, a spring clip carried by each of said sleeves, each clip being constructed from a length of wire having one end bent at right angles and embraced by one of the said sleeves, and a carrier adapted 115 to be embraced by the said clips, the said carrier being provided with mail bag attaching elements.

8. A mail transferring device comprising, 120 a mail bag supporting device, retaining plates carried by the mail bag supporting device, said plates having projecting flanges which latter have their proximate faces in engagement, right angular sleeves connected 125 to the said retaining plates, the said sleeve being arranged in pairs on each side of said retaining plates, a spring clip carried by each of said sleeves, each clip being constructed from a length of wire having one end bent at right angles and embraced 130

by one of the said sleeves, a carrier adapted to be embraced by the said clips, the said carrier being provided with mail bag attaching elements, the said carrier having annular grooves, the said clips being received in the said grooves when the carrier is engaged by the clips.

In testimony whereof I affix my signature in presence of two witnesses.

PHILLIP A. SHAVER.
